[57] CLAIM

The ornamental design for a mounting base for a light fixture
with passive infrared motion detector, as shown and
described.

DESCRIPTION

FIG. 1 is a lower right perspective view, at a reduced scale,
of a mounting base for a light fixture with passive infrared
motion detector showing my new design;

FIG. 2 is a front elevational view thereof; the rear view is
plain and unornamented;

FIG. 3 is a left elevational view thereof, the right elevational
view being a mirror image;

FIG. 4 is a top plan view thereof; and,

FIG. 5 is a bottom plan view thereof.
